Fig. 2.

Fig. 3.

The diagram illustrates a vertical filter assembly. At the top, a horizontal filter (11) is shown with a central vertical filter (12) positioned within its center. Below this, a vertical filter (13) is shown, also with a central vertical filter (12) positioned within its center. The filters are depicted with a hatched pattern. Labels 7, 8, and 12 are placed within the filter sections to identify them.

Pierre Plantenga,
Meskela Saydula,
his Attorneys

UNITED STATES PATENT OFFICE.

PIERRE PLANTINGA, OF CLEVELAND, OHIO.

COKE-OVEN.

1,292,369.

Specification of Letters Patent.

Patented Jan. 21, 1919.

Application filed February 20, 1917. Serial No. 149,935.

To all whom it may concern:

Be it known that I, PIERRE PLANTINGA, a citizen of the United States, resident of Cleveland, county of Cuyahoga, and State of Ohio, have invented a new and useful Improvement in Coke-Ovens, of which the following is a specification, the principle of the invention being herein explained and the best mode in which I have contemplated applying that principle, so as to distinguish it from other inventions.

My invention relates to coke ovens, and particularly to coke ovens in which it is necessary or desirable to regulate and control the heating operation. The object of the invention is to provide a coke oven structure economical of construction and efficient in the performance of its function.

The annexed drawings and the following description set forth in detail certain means embodying my invention, such disclosed means constituting, however, but one of the various mechanical forms in which the principle of the invention may be employed.

In said annexed drawings:—

Figure 1 represents a vertical longitudinal section of a coke oven embodying my invention. Figs. 2, 3 and 4 represent vertical sections taken on the planes indicated by the lines II—II, III—III, respectively. Fig. 1, and IV—IV Fig. 3.

The illustrated embodiment of my invention comprises a plurality of pairs of parallel regenerators 1, each including the usual checker-work. Each of these pairs is composed of two regenerators, a front regenerator shown at the left of Fig. 1, and a rear regenerator shown at the right. Each member of each pair of regenerators is separated from the other thereof by means of a center vertical wall 16. A duct 2 communicates with the bottom of the front regenerator and a duct 3 with the bottom of the rear one, these ducts alternately acting as outlets for the gases of combustion to the stack as will be readily understood by those skilled in the art. A distributing chamber 4 is formed beneath each pair of regenerators, as shown in Fig. 1, and valves 14 are provided for controlling communication between them and ducts 2 and 3. Each chamber 4 is connected with an air-supply pipe 5, communication through which is controlled by a suitable valve 6, as shown in Fig. 1.

Communicating directly with the top of the regenerators, respectively, are two dis-

tributing chambers 20, and communicating with each of them is a plurality of upright intake ducts 7, the tops of each of which communicates with two adjacent heating-flues 8, one in front and one at the rear of each duct 7. A set or series composing a plurality of uptake ducts 7 and heating-flues 8, is placed between the walls adjacent to the coking-chambers 21, the longitudinal dimensions of the latter being parallel with the longitudinal dimensions of the regenerators, as will be understood. The lower ends of each series of heating-flues 8 communicates, by means of openings 9, with an intermediate horizontal heating-flue or chamber 10, which extends throughout the length of the oven above the regenerators and beneath the coking-chamber. The communication through these openings and hence the heating at this zone is regulated by means of suitable valves 15.

Extending along the upper part of the oven is a plurality of gas supply pipes 22, one of such pipes being provided for each set of flues 7 and 8. From these pipes extend downwardly the gas supply ducts 11 for supplying the burners 12, the lower ends of which communicates with the upper ends of the heating-flues 8, as shown, at which point the gas is mixed with air and burned. Each gas duct 11 is provided with a valve 18, as shown in Fig. 3, whereby the amount of gas admitted for burning may be controlled.

The oven as thus far described operates as follows:

Assuming that the direction of flow of the gases is that indicated by the arrows, air is admitted into the left-hand or first regenerator 1, into the distributing duct 4 and passes upwardly through the checker-work thereof, becoming heated during its passage. This air then passes into the left-hand chamber 20, upwardly through the ducts 7 at the top of each of which it divides and passes over into the downwardly extending heating-flues 8. Before thus passing downwardly, however, it is mixed with the gas from the ducts 11 and burned at the burners 12. The gases of combustion then pass downwardly through the heating-flues 8, out of the openings 9 and into the left-hand or first portion of the intermediate heating-flue 10, whence they pass into the right-hand portion of the latter through the openings 9, upwardly through the heating-flues 8 which now act as mere outlet flues, then down-

wardly through the ducts 7, and into the right-hand chamber 20, thence through the right-hand or rear regenerator into the distributing chamber 4 thereof, and thence out through the discharge or exhaust duct 3.

After this operation has taken place the required length of time, the direction of air and the gases of combustion is reversed by turning the air into the rear chamber 4 and 10 using the duct 2 as the outlet, as will be readily understood by those skilled in the art.

It will be noted that during the above described operation, the intermediate flue occupies a position in the cycle of gas travel substantially half way between the point of air inlet and the discharge outlet. This is also true when the direction of movement of the gases is reversed. By providing the dampers or valves 15 for controlling communication between the heating-flues 8 and the flue 10, regulation is provided in a zone subjected to substantially constant conditions, and a minimum of adjusting of the valves is hence required.

25 In the above-described operation, it will be noted that unmixed air is being supplied to but one-half of the heating-flues of a series, the other half of the heating-flues acting as outlet ducts for the gases of combustion. For the purpose of supplying gas to be mixed with the air and to supply the required heat, but one-half of the ducts 11 need be used during the one operation, and the other half during such operation may be 30 closed, if desired. However, in case it should be found desirable to increase the heating effect of the gases of combustion, the gas from the remaining half of the gas supplying ducts may be burned at the top of the heating-flues of that portion thereof which is on the outlet side of the apparatus.

For instance, in the above-described operation, gas from those ducts 11 on the left hand side of the figure, that is, on the left 45 of a plane passing through the center of the wall 16, is mixed with the air and burned. The gas burners to the right of this plane may be shut off. If, however, it is desired to heat the gases of combustion which are 50 passing through those ducts 7 and 8 to the right of the above-mentioned plane, gas from those ducts 11 above the right-hand section of the apparatus may be burned and thus increase the heating effect of these gases 55 of combustion.

From the above description it will be noted that the temperature of the gases of combustion may be regulated in various degrees.

60 Such regulation, however, may be further amplified by providing additional gas-burning means. These may consist of a plurality of gas pipes 13, one for each set of heating-flues 7 above each regenerator, as shown in Fig. 1. Connected with each of these

70 pipes are upright burners 17, one of the latter being provided for each air-duct 7. These burners discharge the gas into the lower ends of these air-ducts 7, at which point such gas may be burned for the purpose of increasing the temperature if desired, in this zone.

75 Horizontal flues such as the flue 10 have heretofore been provided in certain types of oven, but they have been located at the top of the oven structure and immediately above the heating flues. By so locating this flue at the top, the brick partitions are materially weakened. Since these partitions form the real strength of the oven wall, a 80 material advantage is gained by eliminating this weakness and placing the horizontal flue at the bottom, as above described.

85 This intermediate horizontal flue in practice becomes exceedingly hot and when it is located at the top, it is in a position adjacent to the top of the coking chamber and hence substantially all of the gas manufactured in this coking-chamber must pass adjacent to and hence comes in contact with, these exceptionally highly heated walls of the horizontal flue. This results in the breaking up of some of the gas manufactured in the coking-chamber into carbon and 90 hydrogen, with the consequent loss of valuable hydrocarbons. By locating this intermediate flue at the bottom, however, it will be seen that its heat may be applied to the bottom of the charge of coal where it is most needed and the heated walls of the intermediate flue are adjacent to a portion of the coking-chamber in which practically no gas has yet been formed or at least very little. The liability of loss of hydrocarbon by 95 superheating is therefore reduced in a minimum.

100 By providing the burners as indicated, it is possible to shift the zone of greatest heat so as to obtain a hotter bottom, hotter center or hotter top, as may be advisable or desirable in connection with the particular kind of coal which is to be carbonized.

Having fully described my invention, what I claim and desire to secure by Letters Patent is:—

110 1. In a coke oven, the combination of a coking chamber; a pair of regenerators disposed beneath said chamber; a plurality of heating flues disposed adjacently to said coking chamber; a heating flue disposed intermediately of, and communicating with, a part of said heating flues and the balance of said heating flues; means providing communication between said two sets of heating flues and said regenerators, respectively; means for supplying air to said regenerators, respectively; means controlling said air supplies; means adapted to furnish gas to said air; means controlling said gas furnishing means; burners; discharge ducts com- 115 120 125 130

municating with said regenerators, respectively; and means for opening and closing said ducts.

2. In a coke oven, the combination of a coking chamber; a pair of regenerators disposed beneath said chamber; a plurality of heating flues disposed adjacently to said coking chamber; a heating flue disposed intermediately of, and communicating with, a part of said heating flues and the balance of said heating flues; means controlling said communication between said intermediate flue and said two sets of heating flues, respectively; means providing communication between said two sets of heating flues and said regenerators, respectively; means for supplying air to said regenerators, respectively; means controlling said air-supplies; means adapted to furnish gas to said air; means controlling said gas furnishing means; burners; discharge ducts communicating with said regenerators, respectively; and means for opening and closing said ducts.
3. In a coke oven, the combination of a coking chamber; a pair of regenerators disposed beneath said chamber; a plurality of pairs of heating flues disposed adjacently to said coking chamber; a heating flue disposed intermediately of, and communicating with, some of said pairs of heating flues and the balance of said pairs of heating flues; means providing communication between said regenerators, respectively, and the respective pairs of heating flues of said two sets of pairs of heating flues, respectively; means for supplying air to said regenerators, respectively; means controlling said air-supplies; means adapted to furnish gas to said air; means controlling said gas furnishing means; burners; discharge ducts communicating with said regenerators, respectively; and means for opening and closing said ducts.
4. In a coke oven, the combination of a coking chamber; a pair of separate regenerators disposed beneath said chamber; a discharge duct and an air inlet communicating with each of said regenerators; means controlling said discharge ducts and said air-inlets, respectively; a plurality of heating flues disposed adjacently to said coking chamber; air ducts connecting said regenerators, respectively, with a part of said heating flues and the balance of said heating flues; an intermediate heating flue providing communication between the heating flues of one set and the heating flues of the other set; means controlling the communication between said intermediate heating flue and each of the heating flues of said two sets of

heating flues; means furnishing gas to the air; means for controlling the gas supply; and burners disposed adjacently to said heating flues.

5. In a coke oven, the combination of a coking chamber; a pair of separate regenerators disposed beneath said chamber; a discharge duct and an air inlet communicating with each of said regenerators; means controlling said discharge ducts and said air-inlets, respectively; a plurality of heating flues disposed adjacently to said coking chamber; air ducts connecting said regenerators, respectively, with a part of said heating flues and the balance of said heating flues; an intermediate heating flue providing communication between the heating flues of one set and the heating flues of the other set; means controlling the communication between said intermediate heating flue and each of the heating flues of said two sets of heating flues; means furnishing gas adjacently the connections of said air ducts and said regenerators; burners disposed adjacently said connections; means controlling said gas furnishing means; means furnishing gas adjacently the connections of said air ducts and said heating flues; burners disposed adjacently said connections; and means controlling said last-named gas furnishing means.

6. In a coke oven, the combination of a coking-chamber; a regenerator beneath said chamber; a plurality of heating-flues adjacent to one wall of said coking-chamber; an intermediate heating-flue communicating with said heating flues and with said regenerator; a second regenerator communicating with said intermediate heating flue; means for supplying air to said first-named regenerator and a discharge duct communicating with said second-named regenerator; and means for controlling communication between said intermediate heating-flue and said first-named plurality of heating-flues.

7. In a coke oven, the combination of a coking-chamber; two regenerators adjacent to said chamber; a plurality of heating-flues and air inlet ducts adjacent to one wall of said coking-chamber; an intermediate heating-flue communicating with all of said first-named heating-flues; means for controlling such communication; an outlet-duct for each regenerator; and an air-supply duct for each of the latter; said air-inlet ducts which are adjacent to the coking-chamber wall, communicating partly with one regenerator and partly with the other.

Signed by me this 14th day of February, 1917.

PIERRE PLANTINGA.
